UNITED STATES PATENT OFFICE.

CHARLES CAMPBELL, OF LONDON, ENGLAND, ASSIGNOR TO THE TABULATING MACHINE COMPANY, OF ENDICOTT, NEW YORK, A CORPORATION OF NEW JERSEY.

TOTAL-TAKING DEVICE.

REISSUED

Application filed January 22, 1926, Serial No. 82,933, and in Great Britain February 4, 1925.

This invention pertains to record controlled tabulating machines, having an improvement on the machine disclosed in Canadian Patent No. 247,815, March 17, 1925, issued to F. M. Carroll, and copending United States application Serial No. 607,847, filed December 19, 1922, by the same inventor.

One function of that machine is to accumulate in two accumulators statistical data from a single field of perforated record cards, and to print minor, or sub, totals and major, or grand, totals from the two accumulators, under the automatic control of group perforations in the cards. The same amounts are added in two accumulators, one handling minor totals and the other major totals. When a subgroup control designation changes, a total is taken from the sub total accumulator and that accumulator is cleared or zeroized. The taking of a minor total does not affect the major total accumulator, which continues to add all amounts, regardless of minor group changes, until a major group designation changes, whereupon a major total is taken and the major accumulator cleared, or reset.

Whenever changes of major and minor group designations occur simultaneously, the machine prints either the minor or major total, but does not print both totals, and the principal object of the present invention is to provide improved devices which will enable the machine to print both minor and major totals whenever the minor and major group control designations change at the same time. Briefly, this result is brought about by first printing the minor total and then, if a major group has changed, causing the machine to perform an extra revolution during which the major total is printed. Each accumulator is reset while its total is being taken.

In the drawings,

Fig. 1 is a side sectional elevation of the machine, showing accumulators, printing mechanism, etc.

Fig. 2 is a side view of a portion of the other side of the machine, showing the mechanism of my invention as applied to the machine.

Fig. 3 is a plan view of the mechanism shown in Fig. 2.

Fig. 4 is a wiring diagram of the electric circuits pertaining to my invention.

Provision is made for taking major and

minor totals from the same record cards. The upper shaft 249 (Fig. 1) drives the major total accumulator, and the lower shaft 250 drives the minor total accumulator.

The accumulators are arranged in two banks, the upper accumulators being designated generally 253 and the lower accumulators being designated generally as 254.

Located above the accumulators is the printing drum carried on shaft 161. The drum carries a number of type levers 162, one row of type levers being provided for each column on the card, and the number of the type levers about the drum periphery corresponding to the index point perforations in the card column. These type levers, when engaged by the controlling hook members 163, cause the type to be thrown upwardly to print on the record sheet on the platen.

To control the operation of the type levers 162 for listing items, call-magnets 165 are provided with individual armatures which control and elevate call-wires 166 which extend upwardly and control the printing devices.

Extending downwardly from the printer control mechanism are call-wires 240, each of which actuates an accumulator element 80 through a member 266 to add on that element the amount printed by the type bars to which that accumulator element is correlated.

All the above mechanism, together with the group control devices, is fully described in the patent and application above referred to. For the purpose of the present description it will be sufficient to know that the group control devices comprise upper and lower sets of contact brushes which simultaneously sense the group control perforations of two successive cards. If the perforations are different in the two cards it means that a change of group has occurred, whereupon the total taking mechanism is brought into action, as will appear. When a total is to be taken the total clutch magnet 323 is energized and causes vertical shaft 315 to be turned concurrently with the printing drum. Directly below the total-clutch magnet 323 are two magnets 908 and 903, the former being the grand total controlling magnet and the latter a grand-total pre-selecting magnet. The magnet 908 operates upon an armature 326,

which armature has an operating connection extending to a clutch sleeve 327 surrounding the vertical shaft 315. The armature 326 is urged downwardly (away from the magnet 908) by a spring 920. When the magnet 908 is energized the clutch 328 is engaged, thereby coupling shaft 315 so as to drive a shaft 329 through the skew gearing shown in Fig. 2. When the magnet 908 is deenergized the armature 326 will be moved downwards by compression springs 920, whereby a clutch 330 will be engaged and cause the rotation of a shaft 331.

It may be explained that the so-called total clutch controlled by the total clutch magnet, is a clutch of the one revolution type permitting shaft 315 normally to make one revolution only, although of course it will make more than one successive revolution if the magnet 323 is re-energized at the proper times. Furthermore the gearing is such that the shafts 315, 329 and 331 will rotate once in the same time.

Beneath the pre-selecting magnet 903 is pivoted an armature 905 (Figs. 2 and 3) normally held in its lower position by a spring 921 and having a forked end which embraces a groove in a double dog-clutch member 940 splined to a vertical shaft 941 mounted to rotate in suitable upper and lower bearing plates. This shaft has secured to it at its lower end a gear-wheel 942 in mesh with an idler 952 which is in mesh with a gear-wheel 962 secured to the lower end of the shaft 315, the gear ratio being 1:1.

The shaft 941 also carries two gear-wheels 943 and 944 provided on their hubs with clutch teeth capable of being engaged by the clutch teeth of the member 940. These wheels 943 and 944 are normally free to rotate upon the shaft 941, and are clutched thereto by the engagement therewith of the clutch member 940, the wheel 943 being so clutched when the magnet 903 is deenergized and the wheel 944 when the magnet is energized, as will be readily understood.

A vertical cam-shaft 950 is mounted in bearings adjacent the shaft 941, and has secured to it two gear-wheels 943a and 944a in mesh with the wheels 943 and 944, respectively. The ratio of the wheels 943 and 943a is 1:1, and the ratio of the other pair is 2:1. Thus when the magnet 903 is deenergized, one revolution of the shaft 315 will cause the cam-shaft 950 to make one revolution, but when the magnet 903 is energized the cam-shaft will only turn through one-half a revolution.

The shaft 950 carries a cam 950a of insulating material having one high point which engages and closes momentarily a pair of normally open contacts 478 to be referred to hereinafter. Another pair of normally open contacts 907 are provided which are closed when the magnet 903 is energized by a rod fixed to

and extending upwardly from the armature 905.

A third pair of contacts 910 are provided which are closed momentarily, by a cam 909 secured to the shaft 331, just prior to the end 70 of the rotation of the shaft 331.

The parts just described with reference to Figs. 2 and 3 operate to determine whether a sub-total only, or a sub-total followed by a grand total, shall be taken as will hereinafter 75 be described.

The details of the total taking mechanism and its operation are fully explained in the above patent and application, and it will be sufficient for the present purpose to know 80 that shaft 329 is caused to make one revolution when a major total is to be taken, and shaft 331 must make one revolution when a minor total is taken. The total taking operations carried out by shafts 329 and 331 include the resetting of the accumulators. 85

In the diagram (Fig. 4) brushes 480 are the tabulating brushes; upper and lower brushes 144 and 145 are the group control brushes for minor groups, while upper and lower brushes 144a and 145a are for major group control. 503 and 503a are the minor and major group control magnets, respectively. 482 is the plug board by means of which desired circuit connections are made. 95

So long as the machine is running and successive cards correspond so far as their group designations are concerned, both magnets 521 and 515 will be energized. When a change in either a minor or major group occurs, one 100 or the other of these magnets 521, 515 will be deenergized.

It is the relay circuit marked 523 of these two magnets 515 and 521 which maintains the energization of the card feed clutch magnet 105 95. Consequently, after the circuit 523 is broken by either relay, the card feed clutch magnet will become deenergized at the proper time in the cycle and subsequently a minor or major total will be taken, depending upon 110 the energization of the magnets 908, 903, as will be explained.

The manner in which it is determined whether a sub-total only, or a sub-total and a grand total, shall be printed will first be 115 described.

It should be explained that a sub-total is always required when a grand total is taken, whether the sub-group perforations change or not. For example, there may be two successive main groups representing two railways A and B. Each main group will usually comprise several sub-groups each relating, maybe, to a commodity such as coal or oil. If the last sub group of main group A is coal 125 and the first sub-group of main group B is oil, then the sub-group and main group perforations will change simultaneously. If the last sub-group of A is coal and the first sub-group of B is also coal, then the sub- 130

group perforations will not change. But a sub-group total of A's coal must be taken, and the sub-group accumulator cleared, before the machine re-starts to tabulate B's 5 cards, otherwise A's coal will be added to B's next sub-total.

Consequently, whenever the machine stops as a result of a change of group perforations, whether sub-group or main group or both, a 10 sub-total must be printed, to be followed by a grand total only if the main group perforations have changed.

Reverting now to Figs. 2 and 3, it will be noted that the springs 920 normally hold the 15 clutch-sleeve 327 in its lower position to clutch the sub-group accumulator shaft 331 to the resetting shaft 315. Only when the magnet 908 is energized is the clutch-sleeve 327 raised by armature 326 to clutch the main 20 group accumulator shaft 329 to the shaft 315. Consequently it is necessary to energize the magnet 908 (when a grand total is to be 25 printed) at the end of one revolution of the shaft 315 and to provide for a second revolution of the latter. If no grand total is to be 30 printed the magnet 908 is not energized and the shaft 315 need only make one revolution.

When a change occurs in the sub-group perforations only, the magnet 515 (Fig. 4) is de- 35 energized and consequently the card-feed is stopped as previously described and cams, known for convenience as E cams, function to cause the total-taking and resetting shaft 315 to rotate, as is fully described in the above 40 mentioned patent and application. As the main group perforations have not changed, the magnet 521 is energized and attracts an armature 900 (Fig. 4), thereby opening a circuit A-B in which is placed the winding of 45 the magnet 903 shown in Fig. 2 and known as the grand total pre-selecting magnet. The armature 905 of this magnet therefore remains in its lower position, retaining the clutch-member 940 in engagement with the 50 gear-wheel 943. Consequently the cam-shaft 950 rotates once during the single revolution of the shaft 315. As will be seen from Fig. 3, the winding of the grand-total controlling magnet 908 (which must be energized as al- 55 ready stated to take a grand total) is in a circuit C-D containing the contacts 907 which are closed only when the magnet 903 is energized. Consequently the magnet 908 will not be energized, the sleeve 327 will re- 60 main in its lower position and only a sub-total will be taken. Just prior to the end of the single revolution of the shafts the cam 909 closes the contacts 910 in the circuit C-D, but as the contacts 907 remain open the mag- 65 net 908 remains nevertheless deenergized.

The cam 950a will close the contacts 478 at the end of the single revolution thereby re-energizing the card-feed clutch-magnet and stopping the action of the E cams, as previously described, and the machine will con-

tinue on the next sub-group of cards. It will be noted that only one total taking and resetting cycle has been performed.

Should the main group perforations change, but not the sub-group perforations, 70 the magnet 521 will be deenergized (stopping the card-feed as previously explained) and the armature 900 will not be attracted. There will therefore be a circuit from A through cam contacts 901 (closed just prior 75 to the stoppage of the card-feed) contacts 900, relay 902, grand-total pre-selecting magnet 903 to B, this circuit being maintained by the closure of contacts 904 (prior to the stop- 80 page of the card-feed) and armature of re- lay 902.

The energized magnet 903 will raise its armature 905, closing the contacts 907 and throwing the clutch-member 940 into engagement with the gear-wheel 944. The sleeve 327 being still in its lower position and the shaft 331 in gear with the shaft 315, the ensuing rotation of the latter will bring about a taking of a sub-total, as before. At the end of this rotation, however, the cam-shaft 950 will have made only a half-revolution, 90 since the gear-wheels 944, 944a have a 2:1 ratio. Consequently, the contacts 478 will still be open.

But the contacts 910 will be closed at the 95 end of the revolution of the shaft 315 as before. The contacts 907 being closed, the circuit C-D through the winding of the grand-total controlling magnet 908 will be completed, thus raising the clutch-sleeve 327 and placing the grand-total accumulator shaft 329 in gear with the shaft 315; this circuit C-D being held closed (in spite of the re-opening of contacts 910) by a holding relay 912, as will be apparent from Fig. 4. Since 100 the contacts 478 are still open, the E cams will still function and a second revolution of the shaft 315 will occur, thus taking a grand total. At the end of this second revolution the cam 950a will close the contacts 478 momentarily 110 and thereby re-energize the card-feed clutch magnet 95, thus starting a new tabulating operation on the cards of the next main group and stopping the action of the E cams.

The cam-contacts 911 will thereupon open, 115 thus deenergizing the magnet 908 and the relay 912, and the armature 326 will cease to be attracted. Consequently the spring 920 will return the clutch-sleeve 327 to its lower position, thus disengaging the grand-total ac- 120 cumulator and placing the sub-total accumu- lator in gear with the shaft 315 in readiness for the next sub-total taking operation.

Further, as soon as the card-feed is re- 125 sumed, the cam contacts 904 will open, thus deenergizing the holding relay 902 and the pre-selecting magnet 903, the armature 905 will be returned to normal by its spring 921 and the clutch-member 940 will move out of engagement with the gear wheel 944 and re- 130

engage with the gearwheel 943. All the parts are therefore returned to their original position in readiness for the taking of the next sub-total.

5. It will be apparent that if the sub-group perforations change at the same time as the main-group perforations the sequence of operations will be the same as has been described for a change of main-group perforations 10 only, since a change of sub-group perforations does not alter the position of the clutch-sleeve 327—that is to say, a sub-total will first be taken and afterwards a grand total, followed by a return of all the parts to normal.

15. I claim:

1. In a machine of the class described, in combination, devices for sensing major and minor group designations, means for accumulating major and minor group totals, and 20 means controlled by the major group sensing device for printing minor group totals whenever major group designations change.

2. In a machine of the class described, in combination, devices for sensing major and 25 minor group designations, means for accumulating major and minor group totals, means controlled by the major group sensing device for printing both major and minor totals whenever major group designations change, 30 and means automatically brought into operation upon a change in major group designations for delaying the printing of the major total until the minor total has been printed.

3. In a machine of the class described, in 35 combination, devices for sensing major and minor group designations, means for accumulating major and minor group totals, a resetting member common to both accumulators, and means operable when a major group 40 designation changes to cause said resetting member to first reset said minor group accumulator and then reset said major group accumulator.

4. In a machine of the class described, in 45 combination, devices for sensing major and minor designations, means for accumulating major and minor group totals, means controlled by the major group sensing device for printing minor group totals whenever 50 major group designations change, and means also effective upon a change of major group designations for effecting the further printing 55 of a major group total.

5. A machine having means for sensing 55 minor and major group designations, means for accumulating major and minor group

totals, means controlled by the minor group sensing devices upon a change of a minor group designation for effecting the printing of a minor group total, and means controlled 60 by the major group sensing means irrespective of a concurrent change of a minor group designation for effecting the subsequent printing of a major group total.

6. In a machine of the class described, in 65 combination, devices for sensing major and minor group designations upon record cards, means for accumulating major and minor group totals, means under the control of the minor group sensing devices for printing minor group totals, and means effective for operation upon a change of a major group 70 designation for printing both a major group total and a minor group total.

7. In a machine of the class described, in 75 combination, devices for sensing major and minor group designations upon record cards, means for accumulating major and minor group totals, means under the control of the major group sensing devices for successively 80 printing a minor group total and for thereafter printing a major group total.

8. In a machine of the class described having sensing devices for sensing both a minor and major group designation, multiple accumulators for accumulating major and minor group totals, and means effective 85 upon the sensing of a change in major group designations and operating irrespective of the sensing of the minor group designation for 90 effecting two printing operations by the machine, said means effecting the printing of a minor group total followed by the printing of a major group total.

9. In a machine of the class described, in 95 combination, devices for sensing major and minor group designations upon record cards, and means for separately accumulating major and minor group totals, and means under the control of certain of the aforesaid 100 sensing devices and effective upon a change of certain group designations for effecting an automatic sequential total printing operation by the machine, said means including devices for first taking a total from one accumulator containing the total of one of the groups and for thereafter taking a total from another accumulator containing a total of another group.

In testimony whereof I hereto affix my 110 signature.

CHARLES CAMPBELL.
